UNITED STATES PATENT OFFICE.

WILLIAM E. CANEDY, OF CHICAGO HEIGHTS, ILLINOIS, ASSIGNOR TO
THE CANEDY OTTO MANUFACTURING COMPANY, A CORPORATION
OF ILLINOIS.

CHIMNEY FOR BLACKSMITHS' FORGES.

SPECIFICATION forming part of Letters Patent No. 693,838, dated February 25, 1902.

Application filed December 11, 1901. Serial No. 85,525. (No model.)

To all whom it may concern:

Be it known that I, WILLIAM E. CANEDY, residing at Chicago Heights, in the county of Cook and State of Illinois, have invented certain new and useful Improvements in Chimneys for Blacksmiths' Forges, of which the following is a specification, reference being had therein to the accompanying drawings.

This invention relates to chimneys for blacksmiths' forges.

The object of the invention is to produce a chimney or draft-flue with a movable funnel or intake, which funnel can be moved to present its mouth nearer to or farther away from the forge-fire, and thus permit the application of different forms of work to the fire, at the same time presenting the intake as close as possible to the fire, so as to draw in as much of the smoke and gases of combustion as possible.

In the drawings, which are not made to proportions, but are intended as a suggestive guide to the skilled mechanic, Figure 1 is a perspective view showing the funnel and part of the chimney or draft-flue connected to a forge-shield of common form. Fig. 2 is a vertical central section of the same, indicating in dotted lines a different position of the funnel. Fig. 3 is a detail plan of mechanism by which the funnel may be swung and held in adjusted position. Fig. 4 is a sectional view of trumpet-mouth detached.

Let A indicate a shield of common construction, being essentially a plate of metal, with means for attachment to the hearth B or to the frame of a forge. The form or size of this shield is not material to the present invention, as such shields are made of various forms and dimensions. Rods or braces C, 35 suitably connected to the shield and to the forge frame or hearth, serve to support the shield and steady the same. For convenience of construction and shipment I prefer to make the shield, draft-flue, and funnel a portable 40 structure, which with slight alterations can be attached to many well-known forges as already constructed. The lower edges of the shield may be turned forward and connected to the braces C, if desirable. Near the top of 45 the shield there are projecting lugs or brackets D, extending to the front of the shield.

These lugs may be secured to the top of the shield by the same rivets or fastening devices which hold the braces C. The permanent draft-pipe E extends between the brackets D 55 and may connect in any suitable or usual manner with a chimney or flue.

The movable funnel F is pivoted within the lower end or mouth of draft-pipe E. The pipe E does not extend into proximity with the fire, 60 but terminates at its lower end considerably above the fire. The movable funnel F forms a practical continuation or downward extension of said pipe E and is the only inlet by which smoke and gases can enter pipe E. For 65 convenience in making a joint the upper end of funnel F has convex metallic bars or bushings G attached to its outer surface. The upper end of funnel F, with bushings G attached, fits neatly into the lower end of pipe 70 E. The funnel is pivoted to the draft-pipe and to the ears D by bolts or pivots H, passing through the sides of the funnel and through the draft-pipe and lugs. The funnel F so supported on its pivot is in position 75 to swing from said pivoted supports and still preserve a fairly-close joint between the funnel and draft-pipe, no matter into what position within the ordinary conditions of use the parts may be moved.

The funnel-body is usually made of sheet metal, and for convenience of construction and packing the flaring or bell mouthpiece I is made detachable and will slide down over the tapering body of the funnel F and find 85 its seat at the mouth of the funnel. Various forms of mouthpiece may be substituted.

The forge-fire on hearth B is of greater or lesser quantity and distance from the shield, according to the conditions of the work, within 90 the limits, of course, that the center of the fire is substantially over the twyer or air-supply to the fire.

The joint by which the funnel F is supported may be so tight as to support the funnel 95 in adjusted position by friction. I prefer, however, that mechanism shall be provided for holding the funnel in adjusted position, and a suitable mechanism for this purpose is illustrated in the drawings.

To each of the braces C a bearing-piece is attached. These bearing-pieces are prefer-

ably small castings embracing the braces C and held at any position thereon by set-screws. The bearing-pieces K K' are made to slip readily on the rods or braces C. One piece K' has a cup L, into which a coiled spring M is inserted. The bearing K has on the side toward the bearing K' a ratchet-surface K². A rod or shaft O extends from bearing K to bearing K' and has a crank O' 10 behind the funnel-piece F. The rod O bears a fixed rack or spline R, which normally engages the ratchet-surface K² when the shaft O is forced in that direction by the coiled spring M, against which the other end of rod 15 O rests in the recess in bearing-piece K'.

A hand-grasp S permits a person to take hold of shaft O, and by pressing in the spring the clutch members K² R will be disengaged. The shaft O may then be rocked, and the 20 crank O' will be more or less projected to hold the funnel in desired position. On releasing handle S the spring M will cause the clutch members to reengage, thus holding the crank in adjusted position. The weight 25 of funnel F can generally be depended on to hold the funnel against said crank O'.

The mechanism described is merely a convenient means for holding the funnel in adjusted position.

30 I am aware that a hood has been devised which could be projected more or less over the fire in a forge. Such, however, is not like my invention, since the side support of such hood remained at a fixed distance from 35 the fire, and the opening is larger or smaller, accordingly as the hood is adjusted.

My funnel approaches a mouth of uniform size nearer to or farther from the fire, as desirable. The effect of such a funnel 40 when placed close to the fire is much greater than when at a distance. The proper distance can be arranged according to quality of fuel, draft of chimney, (which may be forced,) and other factors which may arise 45 under different conditions of usage.

What I claim is—

1. In forge-chimneys, the combination of a fixed pipe, supported and having its lower end

some distance above the forge-fire, of a pipe-section hinged thereto and forming a downward continuation of said fixed flue, and means for holding the hinged section in adjusted position relatively to the forge-fire. 50

2. In a forge-chimney, the combination of a metallic shield, a fixed flue-section supported thereby, with its lower end terminating above the forge-fire, and a movable flue-section forming a downward extension of said fixed flue. 55

3. In a forge-chimney, a fixed draft-pipe 60 having its lower terminus some distance above the forge-fire, a hinged funnel-section forming a downward extension of said fixed flue, and means for maintaining a closed joint between the hinged and fixed flue-sections. 65

4. In a forge-chimney, a fixed draft-flue having its lower end supported above the forge, a hinged section forming a downward continuation of said flue, and a flaring mouth-piece constructed to slide over said hinged section. 70

5. The flaring funnel-section having a convex bushing at its upper end, the fixed flue 75 into which said bushing fits, pivots connecting the flue and funnel, and means for holding the funnel in adjusted position, all combined. 75

6. The combination of a forge-shield and inclined braces connected thereto, lugs projecting from the shield, a flue-pipe connected to said lugs, and a funnel-section pivoted to the flue-pipe, all combined. 80

7. The combination of a forge-shield, inclined braces connected thereto, a fixed flue-section on the shield, a hinged funnel pendant from the fixed section, and mechanism supported by the braces by which the funnel may be held in adjusted position, all combined. 85

In testimony whereof I affix my signature in presence of two witnesses.

W. E. CANEDY.
